(57) **ABSTRACT**

A new and distinct *Dracaena* plant named 'PVDRAGQ' which is characterized by the combination of relaxed and somewhat spiraled foliage born on an unbranched stem, variegated foliage with a combination of light green, yellow-green and light yellow irregular axial striations, foliage with broad and irregular yellow margins, and the stability of these characteristics from generation to generation.

2 Drawing Sheets

1

Latin name of the genus and species: The Latin name of the genus and species of the novel variety disclosed herein is *Dracaena fragrans*.

Variety denomination: The inventive cultivar of *Dracaena* disclosed herein has been given the variety denomination 'PVDRAGQ'.

BACKGROUND OF THE INVENTION

Parentage: 'PVDRAGQ' is a spontaneous whole-plant mutation of *Dracaena fragrans* 'Golden Coast' (U.S. Plant Pat. No. 12,603) which was discovered at a commercial greenhouse in San Jose, Costa Rica in 2017. The mutation was initially noted for its unique foliage variegation. Said mutation was isolated for further evaluation to confirm the uniformity and stability of the unique characteristics first observed. Upon confirmation of the stability and uniformity of the characteristics, the new plant was selected for commercialization.

Asexual Reproduction: Asexual reproduction of 'PVDRAGQ' is accomplished by way of rooting stem cuttings. Propagation was first performed in 2017 at the inventor's commercial greenhouse in San Jose, Costa Rica. Through two subsequent generations, the unique features of this cultivar have proven to be stable and true to type.

SUMMARY OF THE INVENTION

The cultivar 'PVDRAGQ' has not been observed under all possible environmental conditions. The phenotype may vary somewhat with variations in environment such as temperature, day length, and light intensity, without, however, any variance in genotype. The following traits have been repeatedly observed and are determined to be the unique characteristics of 'PVDRAGQ'. These characteristics in combination distinguish 'PVDRAGQ' as a new and distinct *Dracaena fragrans* cultivar.

2

1. *Dracaena* 'PVDRAGQ' exhibits relaxed, lorate-shaped foliage born on a single dark green, unbranched stem; and
2. *Dracaena* 'PVDRAGQ' exhibits foliage which is moderately spiraled and curled downward, distally; and
3. *Dracaena* 'PVDRAGQ' exhibits green foliage with light green, yellow-green and light yellow irregular axial striations across the entire foliage surface; broadly and irregularly margined yellow.

BRIEF DESCRIPTION OF THE FIGURES

FIG. 1 illustrates, as nearly true as it is reasonably possible to make the same in color photographs of this type, an exemplary plant of 'PVDRAGQ' grown in San Jose, Costa Rica. This plant, grown in a 15 cm nursery container, is approximately 26 weeks old from a rooted young plant; and

FIG. 2 illustrates, as nearly true as it is reasonably possible to make the same in color photographs of this type, the typical foliage of 'PVDRAGQ'.

BOTANICAL DESCRIPTION OF THE PLANT

The following observations and measurements, made in May of 2019, describe averages from a sample set of six specimens of 26 week-old 'PVDRAGQ' plants grown in 15 cm nursery pots in San Jose, Costa Rica. Plants were produced using conventional greenhouse production protocols for *Dracaena* sp. which consisted of growing under shade cloth, irrigating at regular intervals with ebb and flow flood benches, and fertigation. No chemical treatments of any kind were utilized.

Those skilled in the art will appreciate that certain characteristics will vary with older or, conversely, with younger plants. 'PVDRAGQ' has not been observed under all possible environmental conditions. Where dimensions, sizes, colors and other characteristics are given, it is to be understood that such characteristics are approximations or aver-

ages set forth as accurately as practicable. The phenotype of the variety may differ from the descriptions set forth herein with variations in environmental, climatic and cultural conditions. Color notations are based on *The Royal Horticultural Society Colour Chart*, The Royal Horticultural Society, London, 2015 (sixth edition). 5

A botanical description of 'PVDRAGQ' and comparisons with the parent plant and most similar commercial *Dracaena* cultivar known to the inventor are provided below. 10

Plant description:

Growth habit.—Upright evergreen perennial with foliage born on a solitary unbranched stem. 10

Plant profile.—Obovate to broad elliptical. 15

Average height from base to top of foliage.—87.7 cm. 15

Average width.—Average of 72.2 cm. 15

Growth rate.—Moderately fast growing. 20

Plant vigor.—Moderately to highly vigorous. 20

Propagation details.—Asexual propagation is accomplished by stem cuttings. 20

Time to initiate roots.—Approximately 5 weeks are required to initiate roots at 25 degrees Celsius. 25

Time to produce a marketable 15 cm potted plant.—Approximately 15 to 30 weeks. Pinching will increase lateral branching. 25

Disease and pest resistance or susceptibility.—Neither tolerance nor resistance to normal diseases and pests of *Dracaena fragrans* have been observed. 30

Environmental tolerances.—Adapt to USDA Hardiness Zones 10 through 12 and temperatures as high as 40 degrees Celsius; moderate tolerance to rain and wind. 30

Root system:

General.—Fibrous; freely branched and moderately dense rooting. 35

Distribution in the soil profile.—Shallow to moderately deep. 35

Texture.—Smooth; glabrous. 40

Color.—Greyed-orange, RHS N170A. 40

Stems:

Branching characteristics.—Not freely branched in nature; develops lateral branches only when manipulated by man by way of pruning. Naturally produces one main stem arising from the plant's base. 45

Attitude.—Near vertical. 45

Strength.—Very strong. 50

Length.—55.5 cm. 50

Diameter.—Average 1.9 cm. 50

Internode length.—Average 1.2 cm. 55

Stem texture.—Glabrous; smooth. 55

Stem luster.—Slightly glossy. 55

Color, developing stems.—Yellow-Green, nearest to RHS 144D. 55

Color, mature stems.—Yellow-Green, nearest to a mixture of RHS 145A and 146A. 55

Color at the internodes.—Yellow-Green, nearest to RHS 146A. 55

Foliation:

Arrangement.—Spiraled. 60

Attachment.—Sheathed. 60

Division.—Simple. 60

Attitude.—Foliation near the apex is upright to outward and becomes progressively more relaxed towards the base. 65

Number of leaves per lateral branch.—48. 65

Lamina.—Dimensions — 41.1 cm long and 7.0 cm wide, on average. Shape — Lorate. Aspect — Lightly to moderately axially twisted (i.e. spiraled); distal portion on the lamina pointing downward. Apex — Acute with a short, soft but pointed tip. Base — Sheathed. Sheath — Length — 4.4 cm. Width — 2.0 cm. Color, adaxial surface — Green-white, nearest to RHS 157A. Color, abaxial surface — Nearest to in between green and yellow-green, RHS NN137A; axially striped yellow-green, RHS 145A. Margin — Entire; coarsely undulate. Texture and luster of adaxial surface — Smooth, glabrous and moderately glossy. Texture and luster of abaxial surface — Smooth, glabrous and matte. Color — Juvenile foliage, adaxial surface — Yellow-green, nearest to in between RHS 144A and 146B; central zone is axially striped yellow-green, nearest to a mixture of RHS 144C and 145A; broadly marginated yellow-green, nearest to RHS 144C. Juvenile foliage, abaxial surface — Nearest to in between green and yellow-green, nearest to RHS 138B and 147B; central zone is axially striped yellow-green, nearest to a mixture of RHS 144D and 147D; broadly marginated yellow-green, nearest to RHS 144D. Mature foliage, adaxial surface — Nearest to in between green and yellow-green, RHS NN137B and 147A; axially striped yellow-green, nearest to a mixture of RHS 144C, N144C and 146C; broadly marginated yellow, nearest to RHS 12B. Mature foliage, abaxial surface — Nearest to in between green and yellow-green, RHS 137C and 147B; central zone is axially striped yellow-green, nearest to in between RHS 144B and 144C; broadly marginated yellow, nearest to RHS 8B. Venation — Pattern — Parallel. Color, adaxial surface — The main vein nearest yellow-green, nearest to a mixture of RHS 144A, N144C, and 146C. All other veins are indistinguishable from the surrounding foliage: nearest to in between green and yellow-green, RHS NN137B and 147A; axially striped yellow-green, nearest to a mixture of RHS 144C, N144C and 146C; broadly marginated yellow, nearest to RHS 12B. Color, abaxial surface — The main vein is yellow-green, nearest to a mixture of RHS 145C and 145D. All other veins are indistinguishable from the surrounding foliage: nearest to in between green and yellow-green, RHS 137C and 147B; central zone is axially striped yellow-green, nearest to in between RHS 144B and 144C; broadly marginated yellow, nearest to RHS 8B.

Inflorescence: To date, flowering has not been observed. 65

Flower buds: To date, flowering has not been observed. 65

Flower: To date, flowering has not been observed. 65

Reproductive organs: To date, flowering has not been observed. 65

Seed and fruit: To date, flowering has not been observed. 65

COMPARISONS WITH THE PARENT PLANT

Plants of the new cultivar 'PVDRAGQ' may be distinguished from its parent, *Dracaena fragrans* 'Golden Coast' (U.S. Plant Pat. No. 12,603), by the characteristics described in Table 1. 65

TABLE 1

Characteristic	'PVDRAGQ'	'Golden Coast'
Foliage attitude.	Foliage is generally more relaxed.	Foliage is generally more upright.
General coloration of the foliage.	Green foliage with light green, yellow-green and light yellow irregular axial striations across the entire foliage surface; broadly and irregularly margined yellow.	Green foliage with broad, light green to light yellow axial striations towards the margined margins; narrowly yellow.

Plants of the new cultivar 'PVDRAGQ' may be distinguished from the closest known commercial comparator, the common form of the species *Dracaena steudneri* (not patented), by the characteristics described in Table 2.

TABLE 2

Characteristic	'PVDRAGQ'	<i>Dracaena steudneri</i>
Foliage aspect.	Less spiraled (i.e. axially twisted)	More spiralled.

TABLE 2-continued

Characteristic	'PVDRAGQ'	<i>Dracaena steudneri</i>
5 Foliage attitude.	Lower foliage is more upright than those of <i>Dracaena steudneri</i> .	Lower foliage is more relaxed than those of 'PVDRAGQ'.
10 Internode length.	Longer internodes compared to <i>Dracaena steudneri</i> .	Shorter internodes compared to 'PVDRAGQ'.
15 General coloration of the foliage.	Green foliage with light green, yellow-green and light yellow irregular axial striations across the entire foliage surface; broadly and irregularly margined yellow.	Has medium green leaves; no variegation.

That which is claimed is:

1. A new and distinct cultivar of *Dracaena* plant named 'PVDRAGQ', substantially as described and illustrated herein.
